Serge Krimnus; Dino Varmaz(57) **CLAIM**

The ornamental design for an electronic hookah pod, as shown.

DESCRIPTION

FIG. 1 is a top perspective view of the electronic hookah pod of the present invention.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof; and,

FIG. 7 is a bottom perspective view thereof.

The broken line showing of portions of the electronic hookah pod depicts environment and forms no part of the claim.
